UNITED STATES PATENT OFFICE.

JOHN ROY STARK, OF RACINE, WISCONSIN, ASSIGNOR TO WEBSTER ELECTRIC COMPANY, OF RACINE, WISCONSIN, A CORPORATION OF WISCONSIN.

INSTRUMENT-BOARD LAMP.

Application filed May 3, 1922. Serial No. 558,119.

To all whom it may concern:
Be it known that I, JOHN ROY STARK, a citizen of the United States, and resident of Racine, in the county of Racine and State 5 of Wisconsin, have invented a certain new and useful Improvement in Instrument-Board Lamps, of which the following is a full, clear, concise, and exact description, reference being had to the accompanying 10 drawings, forming a part of this specification.

This invention relates to improvements in electric lamps such as are ordinarily employed on the instrument boards of automobiles to facilitate in the operation of the apparatus.

The object of the invention is to provide a lamp of this character which may be readily removed from the instrument board and converted into a portable lamp such as the ordinary trouble lamp employed about an automobile.

In the drawings:
Figure 1 is a transverse sectional view 25 through an automobile instrument board, the instrument board lamp of the invention and the reel for the twisted pair of electrical conductors leading thereto;

Figure 2 is a section on the line 2—2 of Figure 1 looking in the direction of the arrows;

Figure 3 is a vertical sectional view through the drum and housing substantially on the line 3—3 of Figure 1;

Figure 4 is a section on the line 4—4 of Figure 3 looking in the direction of the arrows;

Figure 5 is a section substantially on the line 5—5 of Figure 3 looking in the direction of the arrows;

Figure 6 is a sectional view through the "stick-on" magnet of the lamp and the lamp socket contacts; and

Figure 7 is a circuit diagram showing the 45 connections for the various instrumentalities employed in the invention.

It is believed the invention will be best understood by a description thereof taken in connection with the accompanying drawings.

Referring now to the drawings, in which like reference characters indicate like parts in the several figures, 10 indicates an instrument board such as ordinarily employed on an automobile. Within the opening 11 in

the instrument board is located the collar 12. The collar 12 is substantially cylindrical but is provided on the upper side thereof with an outwardly curved portion which forms the notch or recess 13 adapted to receive the 60 conductors of the twisted pair 14. Secured to the flanges 15 and 16 of the collar 12, by means of the rivets 17, is the housing member which consists of the substantially semi-circular edge portion 18 having the front 65 portion 19 integral therewith and the side members 20 and 21 secured to the parts 18 and 19 in any suitable or desired manner.

Non-rotatably mounted in the plates 20 and 21 is a shaft 22. Rotatably mounted 70 on the shaft 22 is a reel which consists of the sheet metal side pieces 23 and 24 joined together by means of the cylindrical member 25 secured to the side pieces 23 and 24 by the rivets 26. Within the recess between the 75 central portions of the plates 23 and 24 is positioned a spring 27 such as the well-known clock spring, one end of which is secured to the shaft 22, the other end being provided with a hook 28 arranged to engage 80 one end of the cylindrical member 25, as shown in Figure 1.

The spring 27 is arranged to normally tend to rotate the reel in a counter-clockwise direction, as viewed in Figures 1 and 4, so 85 as to wind the twisted pair 14 thereon.

Pivots supported on the reel member 23 is a pair of dogs or pawls 29 arranged to cooperate with the notches 30 in the shaft 25 so as to maintain the reel in any desired adjusted position. The lugs 31 are struck up 90 out of the plate 23 in order to provide stops for limiting the backward movement of the dogs 29.

Positioned between the plate 24 and the 95 side member 21, and surrounding the shaft 22 is a block 32 of non-conducting material. Suitably secured within the circumference of the cylindrical block 32 is a pair of collector rings 33 and 34. The binding post 35 100 is electrically connected to the collector ring 32, while binding post 36 is electrically connected to the collector ring 34 as will be clear from an inspection of Figure 3 of the drawings.

Insulatively secured to the plate 24 and the cylindrical member 26 at diametrically opposite sides thereof are the brushes 37 and 38. Brush 37 at its free end is provided 105 with the inwardly extending flanges 39 110

which are arranged to straddle the collector ring 33 and remain in engagement therewith upon rotation of the reel. In like manner the brush 38 is provided with flanges 40 which in a similar manner are arranged to overlie the edges of the collector ring 34. The ends of the conductors of the twisted pair 14 are connected to the brushes 37 and 38 respectively through the medium of the 10 hollow rivets or eyelets 41. Thus, it will be observed that through the medium of the binding posts 35 and 36, collector rings 33 and 34, brushes 37 and 38, and the conductors of the twisted pair 14, a circuit may be 15 extended through the reel to the terminals of the lamp socket which will presently be described.

Referring now to Figure 1, 42 indicates the base of the instrument lamp arranged to 20 be inserted within the socket 43. The socket 43 may be formed in any desired manner, but is preferably made by turning downwardly portions integral with the inwardly directed flange 44 of the housing member 25 45. Positioned within the enlarged portion 46 of the housing member 45 is a "stick-on" magnet which consists of the metallic core 47 having the winding 48 thereon. Secured to the core piece 47, by means of the reduced 30 portion 49, is a washer 50 of rigid insulating material. The washer 50 is adapted to engage the shoulder 51 in the housing member. A washer 52 is provided about the core 47 in the opposite side of the winding 48, the 35 whole magnet structure being retained in position by a split expanding ring 53 which is partially received by a recess 54 in the cylindrical portion 46.

Secured to the washer 50 by means of the 40 hollow rivets or eyelets 55 is a disc of rigid insulating material 56. The disc 56 is spaced from the washer 50 by means of the collars 57 about the rivets 55. The rivets 55, in addition to securing the disk 56 in 45 position, also pass through the base of the lamp socket terminal spring contacts 58.

Pivottally secured to the insulating disc 56 by means of the eyelet 60 is a metallic switching arm 61 provided with a handle 62 which projects outwardly through a slot 63 in the housing member 45. The inner end of the switch arm 61 is arranged to engage the contacts 64 and 65 in the nature of rivets or studs mounted in the insulating 55 disc 56.

A cap or shell 67 has a cylindrical portion which is adapted to snugly engage the outer surface of the housing member 45 and be retained in position thereby. The cap 67 60 may be provided on one side thereof with an opening 68 of any desired contour through which the light from the lamp 69 may shine.

The enlarged portion 46 of the magnet 65 housing is arranged to fit snugly within the

collar 11. The member 46 is provided on the lower side thereof with a lug 70 adapted to be received by a bayonet slot 71 in the collar 11, so that the instrument lamp when placed within the collar will not be likely 70 to be accidentally disengaged but may readily be removed therefrom when desired.

Positioned about the collar 11 is a plate 72 having an outwardly extending flange 73 which follows closely the contour of the 75 outwardly extending edge of the collar 11. The flange 73 is provided with a notch 74 through which the handle 62 of the switch arm 61 may pass.

The circuit connections for the various 80 parts of the device will now be described, reference being had to Figure 7.

The source of energy 75 is shown connected to the binding posts 35 and 36, which are permanently connected to the collector 85 rings 33 and 34. The collector rings 33 and 34 are normally engaged by the brushes 37 and 38 to which are joined the terminals of the conductors 76 and 77, which together form the twisted pair 14, previously referred 90 to. The conductor 76 at its end remote from the brush 38 is electrically connected to the switch lever 61, arranged to engage the contact 64, or both contacts 64 and 65, depending on its rotary position. The conductor 77 is connected to one of the switch socket contacts 58, and also to one side of the winding 48 of the stick-on magnet. The other side of the winding 48 is joined by means of the conductor 78 to the contact 65. The right lamp socket contact 58, as seen in Figure 7, is electrically joined to the switch contact 64. If desired, the conductor 79 joining one pole of the battery 75 to the binding post 36 may have included in it 105 contacts 80 of the usual switch employed on the instrument board of the automobile, by means of which the instrument lamp is caused to glow.

It will be noted that when the switch arm 110 61 is moved to engagement with the contact 64, a circuit is completed from battery through conductor 79, binding post 36, collector ring 34, brush 38, conductor 76, arm 61, contact 64, to one lamp socket terminal, 115 and from the opposite pole of the battery through binding post 35, collector ring 33, brush 37 and conductor 77 to the other lamp socket terminal 58. It will be noted that at this time the circuit for the stick-on magnet 120 winding 48 is open at contact 65. If, however, the switch arm 61 be moved further so as to engage both contacts 64 and 65, the above traced circuit will extend in parallel from the arm 61 to the lamp socket contact 125 58 and to one side of the magnet, and in parallel from the conductor 77 to the opposite lamp socket contact 58 and the other side of the winding 48. Thus, when the switch arm 61 is moved to an intermediate 130

position, a circuit is completed only for the lamp, and when moved to its extreme operative position, both the lamp and the magnet windings will be included in parallel in 5 the circuit.

Referring again now to Figures 1 and 2, it is to be understood that the slot 74 in the flange 73 is of sufficient length only to permit the switch lever 61, when rotated in 10 a clockwise direction, to assume an inoperative position where it engages neither contact 64 nor 65. When, however, it is rotated in a counter-clockwise direction so that the arm 62 engages the end of the slot 74, the 15 arm 61 will be in a position to engage contact 64 only so as to complete a circuit for the instrument lamp. This arrangement prevents the wasting of current by closing a circuit for the magnet 48 while the lamp 20 is in its position on the instrument board. The slot 63, however, in the housing 45 is of sufficient length to permit the switch arm 61 to be moved to a position where it will engage both contacts 64 and 65, thus 25 completing a circuit for the magnet and lamp in parallel, as above described. If desired, the handle 62 may be moved to the extreme counter-clockwise position on the instrument board, and the circuit then controlled by the switch contacts 80 associated 30 with the usual instrument board light switch.

With the present invention, it becomes unnecessary to provide a trouble lamp, and 35 in case it is desired to use a portable lamp in order to examine the engine or tires, all that is necessary is to grasp the cap 67, give it a slight turn and withdraw the portion 40 46 of the housing member from the collar 41. As the lamp is moved from the instrument board, the twisted pair of conductors 14 will unwind from the reel, and, in an 45 obvious manner, the reel may be caused to remain in its adjusted position. When the device is no longer desired as a trouble lamp, all that is necessary is to give the twisted pair 14 a slight jerk and permit it to be 50 rewound on the reel by means of the spring 27, the lamp being replaced on the instrument board by the reverse of the process by which it was removed.

Although in the accompanying drawings and in the above description applicant has disclosed but one set of details, it is understood 55 that he contemplates many modifications therein, and the invention, therefore, is to be limited merely by the scope of the appended claims.

Having now described my invention, what 60 I claim as new and desire to secure by Letters Patent of the United States is:

1. In combination, a reel arranged to be

secured to one side of the instrument board of an automobile, an instrument lamp socket, means for detachably securing said socket 65 to the instrument board, a lamp contact associated with said socket, a magnet including a winding fixed to said socket, a switching device carried by said socket, a conductor arranged to be wound on said reel and 70 joined at one end to said switching device, said switching device being arranged in one position to isolate said contact and magnet winding, in another position to join said conductor to said lamp contact, and in a third 75 position to join said conductor to said contact and to said winding.

2. In combination, a reel arranged to be secured to one side of the instrument board of an automobile, an instrument lamp socket 80 having a contact, means for detachably securing said socket to the instrument board, a magnet having a winding fixed to said socket, a switching device carried by said socket, a conductor joined to said switching device at one end and adapted to be wound on said reel, said switching device being capable of assuming a plurality of positions, in one of which said contact and said winding are isolated from said conductor, in another of which said contact is electrically joined to said conductor, and in still another of which both the contact and winding are electrically joined to said conductor, and means on the instrument board 85 for preventing said switching device being moved to said last mentioned position when said socket is in position thereon.

3. In a combined instrument lamp and portable lamp, a housing, a lamp socket carried thereby, a lamp contact associated with said socket, a magnet winding carried by said housing, an incoming conductor, a switch within said housing having a plurality of positions, said switch in one position 100 being arranged to electrically isolate said contact and winding from said conductor, in another position to connect said contact to said conductor, and in still another position to connect both said contact and said winding to said conductor, means for detachably securing said housing to the instrument board of an automobile, and means 105 on the instrument board operative when said housing is mounted thereon for preventing said switch being moved to its last mentioned position.

In witness whereof, I hereunto subscribe my name this 28th day of April, 1922.

JOHN ROY STARK.

Witnesses:

E. M. RAY,
Mrs. B. MILLER.
